(57) **CLAIM**

The ornamental design for a blender base interface, as shown and described.

DESCRIPTION

FIG. 1 is a top, front, left side perspective view of the blender base interface;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The details shown in broken lines are for illustrative purposes only and form no part of the claimed design.
